CHARLES F. LEFEVER, OF PLYMOUTH, MICHIGAN, ASSIGNEE TO DAISY MANUFACTURING COMPANY, OF PLYMOUTH, MICHIGAN, A CORPORATION OF MICHIGAN.

LIQUID-PISTOL.

1,143,839.

Specification of Letters Patent. Patented June 22, 1915.

Application filed April 1, 1915. Serial No. 18,487. **REISSUED**

To all whom it may concern:

Be it known that I, CHARLES F. LEFEVER, a citizen of the United States of America, residing at Plymouth, in the county of Wayne and State of Michigan, have invented certain new and useful Improvements in Liquid-Pistols, of which the following is a specification, reference being had therein to the accompanying drawings.

10 The invention relates to liquid pistols, and consists in the provision of a simple and efficient construction of pistol for throwing or discharging liquid; in a structure that may be easily and cheaply manufactured; and further, in the provision of a pistol that may be readily loaded.

The invention resides in the peculiar construction, arrangement and combination of parts as more fully hereinafter set forth.

20 In the drawings,—Figure 1 is a perspective view of a pistol embodying the invention; Fig. 2 is a longitudinal, central section therethrough; Fig. 3 is a section on the line $\alpha-\alpha$ of Fig. 2; and Fig. 4 illustrates 25 a detail of construction.

A designates the barrel of the pistol and B the handle, these parts being preferably made from a sheet metal stamping folded into the form shown. The two sections of 30 the handle are secured together by a rivet C. Arranged within the barrel for movement longitudinally thereof is a member D having a tubular portion E fitting the tubular portion F in the barrel A and provided 35 with a comparatively flat portion G provided with a finger opening H that in effect forms the trigger. The cylindrical portion E and the part G are also formed from a sheet metal stamping folded into the shape 40 illustrated in Fig. 4. Below the cylindrical portion E the barrel A is provided with flanges I spaced to form guides for the portion G. Arranged within the cylindrical portion E at the forward end thereof is a 45 liquid receptacle or cylinder J within which is positioned the head K of the plunger L. The cylinder J is secured in place by an annular flange M at the front of the section E, and a lug N struck inwardly out of the 50 tubular portion E.

O is a lug at the rear of the plunger L, engaging an aperture P in the closed end Q of the barrel A, and R is a spring sleeved 55 upon the plunger L. One end of this spring engages an abutment S on the plunger at

the rear thereof, while the forward end of the spring contacts with a pin T carried by the portion E of the member D.

U is a slot extending longitudinally of the plunger and within which the pin T is arranged.

The spring R acts to project the member D outwardly. Outward movement of the member D is limited by lugs V struck out from the portion G and adapted to engage 65 the inturned flanges W of the handle B.

In use, assuming that the parts are as shown in Fig. 2, to fill the cylinder J with liquid, the operator moves the member D rearwardly to the position shown in dotted 70 lines, and then inserts the end of the pistol into the liquid. The operator then releases the member D and allows the spring R to return the parts to the position shown in full lines in Fig. 2. During the return of 75 the parts to the latter position, liquid will be drawn into the cylinder J through the opening X. To discharge the liquid, the operator then draws upon the trigger H to move the member D to the position shown 80 in dotted lines in Fig. 1.

What I claim as my invention is:—

1. In a liquid pistol, the combination of a barrel, a stationary piston therein including its head and a liquid barrel within 85 which the head is arranged, a movable member arranged in the barrel and carrying the liquid barrel, and a power storing spring adapted to act on said member.

2. In a liquid pistol, the combination of 90 a barrel, a stationary piston therein including its head and a liquid barrel within which the head is arranged, a movable member arranged in the barrel and carrying the liquid barrel, and a power storing spring 95 adapted to act on said member, the latter being provided with a portion forming a trigger.

3. In a liquid pistol, the combination of 100 a barrel, a stationary piston therein including its head, a member arranged in said barrel for longitudinal sliding movement and having a portion projecting therewithout, provided with a trigger part, a power storing spring acting upon said member, and a liquid cylinder arranged in said member within which said head is positioned.

4. In a liquid pistol, the combination of 110 a barrel, a stationary piston therein includ-

ing its head, a member arranged in said barrel for longitudinal movement, a spring acting upon said member to hold the same in one position of adjustment, a liquid cylinder within which said head is arranged, said cylinder being positioned within the forward end of said member and secured thereto against longitudinal movement.

5. In a liquid pistol, the combination of a barrel, a stationary piston therein, a member arranged in said barrel for longitudinal movement, a spring acting upon said member, the forward end of said member being cylindrical, a liquid cylinder arranged in said cylindrical end, and means for retaining said member in said cylindrical end.

In testimony whereof I affix my signature in presence of two witnesses,

CHARLES F. LEFEVER.
